ELECTRIC PLUG

Filed May 8, 1929

Inventor
Leo Savally
By his Attorney
George C. Heinrich

UNITED STATES PATENT OFFICE

LEO SAVALLY, OF NEW YORK, N. Y.

ELECTRIC PLUG

Application filed May 8, 1929. Serial No. 361,474.

This invention relates to improvements in electrical connecting devices and particularly in the construction of plugs used with such connecting devices which ordinarily are provided with an outer thread to engage the inner thread of a socket.

It is the principal object of my invention to provide a plug in which the outer thread is replaced by an elastic and yielding connection allowing a simple and ready application or withdrawal of the plug by imparting to the same a slight pushing or pulling movement respectively, without necessitating a tedious screwing of the plug into its socket frequently causing an undesirable and inconvenient twisting of the cable wires.

Another object of my invention is the provision of a novel and improved plug of simple and therefor inexpensive construction, yet durable and efficient in operation.

A further object of my invention is the provision of a plug allowing the usual attachment of a standard knife blade cap and snugly but firmly engaging the outer threads of a socket, as for instance a chain pull plug socket.

A still further object of my invention is the provision of a novel and improved plug equipped with a metal sleeve, the material of which is cut to form a plurality of socket engaging fingers or tongues.

These and other objects and advantages of my invention will become more fully known as the description thereof proceeds, and will then be specifically defined in the appended claim.

In the accompanying drawing, forming a material part of this disclosure:

Fig. 1 is a front elevation of an electric chain pull plug socket equipped with a plug member constructed according to my invention.

Fig. 2 is a detail view of the plug member and its knife blade cap separated.

Fig. 3 illustrates the use of the plug member as a light socket.

As illustrated, the customary socket member 10 equipped with cap 11, cable 12 and pull chain 13, has its lower end threaded in the usual manner, as indicated at 14.

The separable attachment plug 15 of insulating material has mounted thereon a metal socket 16, the material of the lower edge of which is cut to form a plurality of tongues 17 which are bent outwardly and provided at their extreme outer ends with outwardly directed lips 18 adapted to snugly and firmly engage with their rear bends the threads on the outer face of the lower part of socket member 10.

One of the spring contact fingers 20 is conductively connected with the inner socket member 19, while the other spring contact finger 21 of the plug is conductively connected with the plug contact 22 adapted to engage the contact member 23 of the socket 10.

The plug has the usual openings in its head part allowing the passage of the knife blades 24 of the plug cap 25 connecting with the cable 26 in the usual well known manner.

As illustrated in Figure 3, the plug member 27 may be formed to constitute a socket for a lamp 28, and in this instance the metal socket 29 has its lower edge cut to form a plurality of tongues or lips 30 having their lower extreme ends bent outwardly, as at 31, and engaging with its inner bends or crook 32 the threads on the outer face of the socket 33, the cap 34 of which is attached to a wall arm 35 secured in a wall bracket 36 in the usual well known manner.

The operation of my plug will be evident from the description and drawing, and it will be clear that the plug can be readily attached to the lamp or other socket by simply pushing it inwardly to engage its yielding tongues with the outer threads of the socket 10 in order to establish electrical connection between a source of electricity with any suitable electrically operated apparatus.

In the form of my invention illustrated in Figure 3, the plug has the form of a socket for the reception of an incandescent lamp or light and can readily be engaged with a socket carried by a wall fixture.

It will be obvious that my invention may be adapted to many other types of electrical apparatus, and that I have disclosed the preferred forms of my invention only as ex-

amples of the many possible ways to practically construct the same, and that I may make such changes in the general arrangement of the plug and socket connection and in the construction of the minor details thereof as come within the scope of the appended claim without departure from the gist and spirit of my invention or the principles involved.

Having thus described my invention, what I claim as new, and desire to secure by Letters Patent is:

In an electrical plug, a body of insulating material in form of a frustum having chambers formed therein, a metal socket substantially V-shaped in cross-section with the inner mantle of the V engaging the outer inclined wall of the frustum the outer V mantle bent upwardly and spaced from said first named mantle, and cut to form a plurality of outwardly bent tongues, inwardly bent and outwardly directed lips formed at the extreme outer ends of said tongues adapted to snugly fit and firmly engage with their inwardly bent parts the threads of a socket member to which the plug is to be attached, a plug contact and a spring contact finger in each of said chambers one in connection with said plug contact and the other with said socket for allowing the closing of an electric circuit by engagement by the knife blades of a plug switch.

Signed at New York, in the county of New York and State of New York, this second day of May, A. D. 1929.

LEO SAVALLY.
